UNITED STATES PATENT OFFICE.

HENRY E. WARREN, OF NEWTON, MASSACHUSETTS.

MECHANISM FOR OPERATING VALVES OR EQUIVALENT MEANS OF HYDRAULIC APPARATUS.

SPECIFICATION forming part of Letters Patent No. 752,491, dated February 16, 1904.

Application filed July 7, 1903. Serial No. 164,590. (No model.)

To all whom it may concern:

Be it known that I, HENRY E. WARREN, a citizen of the United States of America, residing at Newton, in the county of Middlesex and 5 State of Massachusetts, have invented certain new and useful Improvements in Mechanism for Operating Valves or Equivalent Means of Hydraulic Apparatus, of which the following is a specification.

10 The improvements relate to what may be termed a "relay" system, in which a small force is employed to put into action mechanism, such as valves or other controllers, to regulate the application of a large force to operate the pistons of hydraulic cylinders or 15 other motors, which may be employed to operate water-gates, elevators, presses, &c.

The invention consists in a normally closed fluid system in communication with a piston 20 or equivalent mechanism connected with the main controller, which may be a valve through which motive fluid is supplied to the main motor or mechanical means, such as clutch mechanism, through which motion is communicated, also in means to produce movement 25 of the fluid within the closed system to operate the controller and means to increase or decrease the fluid capacity of the system in accordance with the movement of the motor in 30 one direction or the other.

A convenient specific embodiment of the improvements is illustrated in the accompanying drawings, wherein—

Figure 1 is a sectional elevation of the improvements combined with a hydraulic piston. Fig. 2 is a similar sectional view with a small cylinder and piston (shown to be operated by hand) to control the fluid in the closed system. Fig. 3 shows a centrifugal speed-governor attached to the valve which controls the fluid for the closed system. Fig. 4 is a sectional elevation of the closed fluid system connected with mechanical means instead of a valve to serve as the controller for the motor. Fig. 5 is a sectional elevation of the apparatus, showing an arrangement by which the controller-valve is operated positively in both directions by pressure of fluid from the primary valve.

The same part of the apparatus is indicated 45 by similar letters throughout the drawings.

Referring to the parts by letter, in Figs. 1 and 2, A represents a hydraulic cylinder, in which moves a piston *b* with its rod *a*. Fluid is admitted to or exhausted from cylinder A through the ports *q* and *r*, which may be connected, by means of the main valve B, with the fluid-inlet *u* or the fluid-outlets *t* and *v*, one port being connected with the outlet at the time when the other is in communication with the inlet in the usual manner of slide-valves. 55 The main or motor valve B is preferably of the well-known balanced type, consisting of two connected pistons *y* and *z* within a cylindrical valve-chamber, through which are cut circumferential openings which register with the ports *q* and *r*, respectively. Fastened firmly to the valve B and preferably forming a part thereof are two plungers or pistons *s* and *x* of unequal cross-sections, which project through glands *z'*. The plunger *s* is smaller 60 than *x*, and, as illustrated, it is acted upon by steady hydraulic pressure furnished through the passage *o*, while the plunger *x* may be acted upon by a variable hydraulic pressure furnished through the inlet *g*. In communication with inlet *g* by means of a pipe *f* is what I will designate a "compensating" cylinder D, in which is a piston or plunger *e*, connected in any suitable manner, but preferably directly by means of yoke *y'*, with the 65 piston-rod *a* of the main motor, so that as the piston *b* moves in its cylinder A the plunger *e* will move simultaneously in its cylinder D. The capacity, therefore, of the cylinder D between its outer end and the plunger *e* 70 will vary with every movement of the piston *b*. Fluid is admitted to or exhausted from this system, which is composed of the valve-chamber *w*, cylinder D, and connecting-passages *f g*, through the pipe *h* and the throttling-valve *i* from the three-way valve C, Figs. 1 and 4. This three-way valve is preferably made in the form of balanced pistons *k*, having linear motion in a cylindrical sleeve containing the ports *n*, *l*, and *m*. Valve *k* 75 has a slight lap over the two outer ports *m* and *n*, but is always in communication through the annular space around the reduced stem with the middle port *l*. Fluid under pressure is admitted through port *m*, preferably from 80

the same source as that which supplies the chamber w' of the valve B, while the exhaust is through the port n . The arrangement is such that whenever the valve k moves up 5 fluid under pressure is admitted through the port m to the annular space around the valve-stem, thence through the port l , throttle-valve i , pipe h , passage g to the chamber w . The fluid in the chamber w is therefore substantially at the same pressure as that in the chamber w' ; but since the cross-sectional area 10 of the plunger α is greater than that of the plunger s the pressure thereon will move the main valve B toward the right, thereby opening the port r to the main exhaust-port v and the port q to the pressure-supply u , thus admitting fluid into the right-hand end of cylinder A, which will move the piston b to the left. This action causes a simultaneous increase 15 in the size of the fluid-space in the compensating cylinder D, and a portion of the fluid flowing through the valve C and the pipe h is immediately diverted thereto instead of continuing to add to that in the chamber w . Through this action it will be observed 20 that very quickly a balance of forces will be reached, whereby the valve B will be held open a certain definite amount, such that the speed of travel of the piston b , and therefore of the plunger e , will be just sufficient to take 25 care of all the fluid which is flowing through the pipe h , for if this were not so the valve B would continue to open until such a condition of affairs had been reached. It will be seen also that as the valve k is gradually 30 closed and the velocity of fluid through the pipe h thereby diminished the speed of motion of the piston b will be diminished, for the plunger e , which moves with it, will make 35 way for fluid in the compensating cylinder D faster than it is flowing through pipe h , and therefore a portion of the fluid in chamber w will be diverted into the cylinder D. During 40 this operation the valve B will travel toward the left, thus closing the ports r and q , substantially in the same ratio as the valve k closes the entrance-port m . When the valve k has closed 45 the entrance-port m completely, motion of the piston b will cease for the reason that the valve B will have moved across and closed the 50 ports q r on account of the escape of sufficient fluid from the chamber w into the compensating cylinder D to permit this. The whole system will then be in equilibrium, and no 55 further movement can take place, for chamber w , cylinder D, and the connecting-passages to the valve C will be full of fluid which cannot escape, and therefore it will be impossible for the main valve B to move in either 60 direction. A movement of the valve k downward will set up action of the piston b in the opposite direction, because a way for escape of the fluid from the chamber w will then be opened through pipe h , throttle-valve i , ports 65 l and p , to the air or a suitable receiver, and

the valve B will therefore be moved to the left by the pressure in the chamber w' , acting against the plunger s . Port q will thereby be opened to the discharge-pipe t and port r to the admission-pipe u , causing the piston b 70 and plunger e to move to the right. The speed of motion will be such as to bring about an equilibrium of forces, so that the fluid-space in the cylinder D will diminish at precisely the same rate as fluid escapes from passage p .

Upon any increase or decrease in the flow of fluid through the pipe h , due to a greater or less opening of the valve C or the throttle-valve i , valve B will move to a new position, 80 and the piston b and plunger e will be moved at a rate to correspond to the change of flow. Since the function of the fluid which flows through the valve C is to move the main valve B a short distance in either one direction or 85 the other, this valve C can be made very small, and therefore easy of movement. It has been found in practice that in order to move a valve like B sufficiently large to supply a cylinder like A, sixteen inches in diameter, for 90 instance, with fluid under two hundred pounds pressure per square inch at a rate which will cause a piston travel of twenty feet or more per minute, the valve k need not be more than three-eighths of an inch in diameter and need 95 not have a total travel of more than one-eighth of an inch. It will thus be seen that my invention provides a most efficient relay device to set into action a very great force through the impulse of a very small one.

In Fig. 3 is illustrated a speed-governor G, combined with the valve C. The governor G is rotated by means of the pulley g' and a belt from the prime motor, and the small primary valve k is connected, by means of the rod h' , 105 with the centrifugal balls in the usual manner. The length of the rod h' is adjusted so that at normal speed the valve k covers the ports m and n ; and, as is well understood, any deviation from the normal speed causes the 110 valve k to be displaced and allows fluid under pressure to move the relaying-valve B and through that to operate the main working piston b .

In the operation of my invention it is generally convenient to utilize the same supply of fluid under pressure for operating the primary and relay valves as that which is used in the main working cylinder; but it is not essential that this should be so, for the primary valve 115 will act upon the relaying-valve just as well if it is supplied with fluid from an independent source, which may be either at a lower or higher pressure.

In order to prevent the possibility of excessive pressure in the chamber w in case the throttle-valve i should be closed and then through some external agency the main piston b , and with it the plunger e , should be moved backward or to the right, thus driving the 125

fluid out of the cylinder D into the pipe f and chamber w, the plunger x at the left-hand end of the relay-valve B may be provided with a small angular passage b', which when the valve 5 B is moved a sufficient distance to the right will permit the escape of the fluid from the chamber w and pipe f into the exhaust-space around the relay-valve B and relieve the excess of pressure.

10 In Fig. 2 is shown a modification of the invention also adapted for use with hydraulic elevators or presses, &c. Herein a small hydraulic cylinder C², with piston k², adapted for hand or automatic control, is substituted for 15 the valve C shown in Fig. 1. By manipulation of the lever h² the piston k² may be moved in or out, thereby forcing fluid from the cylinder C² into the relaying-valve chamber w or allowing a portion of the liquid in the chamber 20 w to flow back into the cylinder C², thus causing a motion toward the right or left of the relaying-valve B, which action results, as heretofore explained, in a motion of the main hydraulic piston b, which through the compensating reaction in the cylinder D returns the relaying-valve B to mid-position. Upon 25 inspection it will be apparent that the movement of the hydraulic piston b will always be such as to increase the capacity of the compensating cylinder D by exactly the amount of decrease of the capacity of the cylinder C², or if the motion is in the other direction to decrease the capacity of the cylinder D by the exact amount of increase of capacity of the 30 cylinder C²—that is to say, there will be a certain linear motion of the piston b for each 35 unit of alteration in capacity of the cylinder C²—and since the change in capacity of the cylinder C² may be readily measured by a 40 pointer moving over a scale or a plunger moving past notches, as shown in Fig. 2, this device makes it possible for an operator to predetermine the movement of the main hydraulic piston for any purpose. For example, an elevator may be operated by the 45 hydraulic piston b and the hand-lever h² have a pointer h³ connected with it and operated by a crank-lever l² and spring l⁴, so that when the pointer is moved over a scale s³ its position of 50 rest would indicate the floor to which the elevator would rise or fall. It should be noted that the motion of the hydraulic piston b takes place after the movement of the piston k², but that its ultimate position will always correspond 55 with the position in which the piston k² comes to rest, (indicated by the pointer h³ on the scale s³,) regardless of the speed of movement of the hydraulic piston b—that is to say, there can be no overtravel of the piston b.

60 For the purpose of partially or wholly balancing the pressure of the fluid beneath the hydraulic piston k² means may be provided for admitting fluid above it at o' under the same pressure as the fluid at o. This device is particularly valuable also in connection with hy-

draulic presses, such as are used for pressing bales of cotton or for forging metal articles, where it is desirable to determine in advance accurately the amount of travel to be given to the main hydraulic piston.

In Fig. 4 is illustrated one form of mechanical means through which movement is communicated to the main motor by the operation of the closed hydraulic system, and it consists of a shaft a', upon which are supported two 75 loose disk-gears y² y³, and secured to the shaft between the disks is a clutch member b². Upon one end of the shaft a' is a piston x', enclosed by a cylinder z', with one end of which the pipe g of the closed fluid system is connected and with the other end of which cylinder the fluid-pipe o is connected. Upon the shaft a' there is also secured a gear a³, which meshes with an internally-threaded gear a⁴. The gear a⁴ is supported with the threaded 80 hole in its hub in line with the compensating cylinder D, and the end of the rod of the plunger e is screw-threaded and extends through the threaded gear a⁴, so that the rotation of that gear in one direction or the other will 85 cause the plunger e to move in or out of the cylinder D. The disk-gears y² y³ are caused to rotate in opposite directions through the pinions v² v³ upon the shaft u². The gear y² 90 engages directly with the pinion v², but the gear y³ is driven by an intermediate pinion t², which meshes with the gear y³ and the pinion v³. The pinion t² is supported upon a counter-shaft t³. It will be understood that when the piston x' occupies the middle position of the cylinder z', as shown in Fig. 4, the clutch member b² will not be in contact with either of the disks y² y³ and that an increase of pressure in the end w of the cylinder z' by the admission of fluid through the valve C will cause the 100 piston x' and shaft a' to move to the right and the clutch b² to engage with the disk y³ and be turned in one direction, while a decrease in pressure at the end w of the cylinder z' by the escape of fluid through the valve C and outlet p will cause the piston x' and shaft a' to move to the left and the clutch b² to engage the disk y² and be turned in the other direction, and, as heretofore stated, through the gears a³ a⁴ the plunger e will at the same 110 time be moved in or out of the cylinder D in accordance with the direction of movement of the gear a³.

It will be understood by those familiar with this art that the linear motion of the rod a 120 may be converted into rotary motion readily by a rack and pinion and the rotary motion of shaft a' into linear motion by the same means, or those shafts may act directly where it is not desired to change the character of the 125 motion.

It is not essential that the valve B should have a constant fluid-pressure tending to move it in one direction, as illustrated in Figs. 1 and 2, where such pressure is exerted upon 130

- a plunger s , extending into the chamber w' . This plunger may have a steady force exerted against it by a spring or by a weight. Neither is it necessary that the primary valve should 5 act to admit fluid into or exhaust it from the chamber w only; but, as shown in Fig. 5, passages h h' may extend from the valve C to each of the chambers w and w' in such a manner as to admit fluid into one and exhaust it 10 from the other simultaneously, in which case it would be unnecessary to have any constant fluid-pressure acting against the plunger s , for the valve would be moved positively in both directions, and the two plungers s and x should 15 have the same cross-sectional area. With such a construction, however, the compensating cylinder D should preferably be made double-ended, as shown, so as to have fluid on both sides of the piston e , and the cylinder D should 20 be connected with the respective chambers w w' by passages f f' . In this construction (shown in Fig. 5) the valve k^3 may be operated by a lever h^4 , either by hand or by connecting it with a speed-governor. In this arrangement also the ports v and t should be 25 the fluid-inlets and u the exhaust or outlet port.

I claim—

1. In combination with a motor, a controller 30 for the motor, a fluid system connected with the controller, means to move the fluid in said system to operate the controller, and mechanism operated by the motor to increase or diminish the fluid capacity of the system in correspondence with the movements of the motor.
2. In combination with a hydraulic motor, a hydraulically-operated valve to control the flow of fluid to the motor, a fluid-chamber con- 35

nected with the valve-operating system, which system is closed when in equilibrium, means 40 to move the fluid in the system to operate the valve, and a plunger in said closed fluid-chamber, which is operated synchronously with the motor to change the fluid-space in the chamber to correspond with the movement of the 45 motor.

3. In combination with a hydraulic motor, a hydraulically-operated valve to control the flow of fluid to the motor, a fluid system to operate the valve, mechanism to control the movement of fluid in said system, a speed-governor to operate said mechanism, and means, operated by the motor, to vary the fluid-space in the system to correspond with the movement of the motor. 55

4. In combination with a hydraulic motor, a controller for the motor, a fluid system to operate the controller, means to determine the amount of movement of fluid in the system, and mechanism, operated by the motor, to vary 60 the fluid capacity of the system in accordance with the movement of the motor.

5. The combination of a motor, a controller for the motor, a fluid system which is connected with each, primary means to alter the fluid-pressure in the system, to displace the controller, and other means connected with the motor, which means act directly upon the fluid in the system in communication with the controller, to restore the latter to its original 70 position. 65
